UNITED STATES PATENT OFFICE

GILBERT M. SCHERER, OF NEW YORK, N. Y., ASSIGNOR TO ROYAL TYPEWRITER COMPANY, INC., OF NEW YORK, N. Y., A CORPORATION OF NEW YORK

TYPEWRITING MACHINE

Application filed October 11, 1927. Serial No. 225,480.

This invention relates to means by which the usual margin stop may be released from the stop bar and held by a part of the frame of the machine while the carriage and stop bar are moved independently of the said stop. This enables the stop to be adjusted to any desired position since if the stop is to be set at any particular letter space position of the carriage, it is only necessary to operate the releasing mechanism, move the carriage to the desired letter space position and release said mechanism, allowing the stop to again engage with the stop bar.

Either of the ordinary margin stops may be adjusted readily and quickly to any desired letter space position. The key which releases the margin stops from the stop bar is also adapted to operate the usual lever which releases the carriage from the escapement mechanism and permits it to be moved in either direction to the desired point.

Further features of the invention will be apparent from the following detailed description and will be set forth in the appended claims.

In the drawings:

Figure 1 is a top plan view of a portion of the carriage showing the margin stops and means for releasing the same.

Figure 2 is a rear view of a margin stop and the associated detent mechanism on the frame of the machine with the parts in normal position.

Figure 3 is a similar view with the margin stops shown in vertical section and the parts in operative position.

Figure 4 is an end view of the typewriter carriage showing the general relation of the invention thereto.

Figure 5 is a top plan view of a margin stop and supporting stop bar with the usual central stop in horizontal section and the two stops in operative engagement.

Figure 6 is a similar view showing the different position of the parts.

Figure 7 is a rear view of the stop bar with part thereof in vertical section and the release bar in normal position.

Figure 8 is a similar view with the release bar in its operative position.

This invention is applicable to a standard form of typewriting machines but for convenience has been illustrated in connection with the standard Royal typewriter.

There is illustrated a platen A mounted in side frames B of the carriage, which frames are connected by a tie rod C. An escapement wheel D is mounted in the main frame E and has rigid therewith a pinion F which meshes with a rack G carried by a bail H having arms K pivotally supported on the side frames of the carriage. A bent lug L on the carriage release lever M underlies one of the arms K so that by operation of the release lever the bail is lifted and the rack G disengaged from the pinion F to permit movement of the carriage in either direction. There is also shown in Figure 4 the usual tabulating stop bar N.

The margin stop bar 1 is supported at its ends in the side frames B of the carriage and has a central longitudinal slot in which slides a release bar 2. The stop bar carries pins 3 which pass through inclined slots 4 in the release bar so that an endwise movement of the release bar from the position shown in Figure 7 will cause the bar to ride upwardly until it projects beyond the edge of the stop bar as shown in Figure 8. This endwise movement is brought about by the following mechanism.

The finger lever 5 is pivoted to one side of the carriage by the same screw 6 which holds one end of the tie rod C in position. This lever has a bent over arm 7 connected by a link 8 to one arm 9 of a bell crank lever pivotally supported on the carriage and having its other arm 10 engaging a cut-out 11 in one end of the release bar 2. A spring 12 which has one end fast to a fixed support on the carriage and the other end passing through a hole 13 in the release bar returns the lever to normal position when pressure is removed from the finger lever 5. The lever 5 also has a pin 14 projecting outwardly and overlying the carriage release lever M so that when the lever 5 is operated, not only will the release bar 2 be moved to its operative position, but the carriage will be released from its escapement mechanism so that

it may move freely in either direction. It will be also observed that the carriage release lever M may be operated independently of the margin stop release lever 5.

5 The margin stops illustrated are in many respects similar to those previously known and used in the Royal machine and each stop comprises a body portion 15 of general trough like form having ears 16 and 17 at 10 their ends which project below the stop bar and are connected by pins 18 and 19 respectively. The thin metal member 20 has its ends hooked about the pins 18 and 19 and lies in contact with the lower edge of the 15 stop bar. The stop is held in adjusted position on the stop bar by means of a latch member 21 provided with a finger piece 22 and having ears 23 intermediate its ends which are pivoted to the stop on an axis 24. The 20 latch member also has a downwardly extending tooth portion or detent 25 which engages between the teeth 26 of the stop bar 1 and holds the stop in its adjusted position. A spring 27 coiled about the pivot 24 tends to 25 return the latch 21 to the Figure 2 position.

Between the body of the stop and the latch member thus described and pivoted on the pivot 24 by means of ears at each side thereof is a bail member 28 normally forced downward by a spring 29. One end of this bail member has a downwardly extending arm 30 provided with a pin 31 at its end which fits in an elongated slot 32 near one 30 end of a detent member 33 which comprises 35 side members connected by a cross bar 34 terminating in a sharp edge. This detent member is pivoted on the pin 19.

The engaging portion of the stop is an adjustable screw 35 carried by the stop member above described and locked in adjusted 40 position by a set screw if so desired. The stop also includes mechanism for automatically setting the stop surfaces a distance away from each other equal to one letter 45 space, such mechanisms being in themselves old as shown for example in patent to L. C. Myers No. 947,450 granted Jan. 25, 1910. This mechanism comprises in the present instance an adjustable member 36 held in position 50 upon the stop member by a screw 37 passing through an elongated opening in the member 36. Upon this member 36 is pivoted by a screw 38, an interponent 39 having an end 40 which may be moved into a position 55 between the stop 35 and the center stop 42 on the frame of the machine. The interponent has an upturned end 41 having a cam portion in position to be engaged by the latch 21 when it is pressed downward to release 60 the stop from the stop bar. Whenever the stop is released either manually or by the release mechanism, this interponent will be swung to the Figure 6 position.

65 The detent member 33 is adapted to cooperate with detent mechanism on the frame of

the machine which comprises a bracket 43 having offset flange 44 which is fastened to a fixed part of the machine by screws 45 which pass through openings 46 in said bracket. Two dogs 47 are mounted on pivots 48 and have their facing ends 49 separated by a slight space. A downward extension of each dog 47 carries a pin 50 which projects through a slot 51 in the bracket member. A spring 52 has a central portion coiled about a stud 53 carried by the bracket and the ends 54 thereof engage the pins 50 to hold the dogs 47 normally in the Figure 2 position.

When the parts are in normal position such as shown in Figure 2, the margin stop is locked to the said bar 1 and the detent 33 is in a plane above the ends 49 of the dogs 47. When it is desired to set a margin stop, the lever 5 is operated, which through the pin 14 will operate the carriage release lever M and at the same time will move the release bar to endwise position. This will cause the release bar to rise to the position shown in Figures 3 or 8 and in this movement it will engage with the detent 25 and lift the same out of engagement with the teeth 26 of the stop bar. At the same time the release bar 2 will engage the bail 28 and rock the detent member 33 downward, bringing the bar 34 into the Figure 3 position so that as the carriage is moved in proper direction, the detent will engage one of the dogs 47 and cam the same downward against the tension of the spring 52 until the end of the detent comes into the space between the ends 49 of the dogs. In this position it will be held so long as pressure is maintained on the lever 5 and at this time the carriage can be moved independently of the stop to any desired letter space position. The same releasing movement of the latch 21 above mentioned will cam the interponent 39 to the Figure 6 position to automatically set the marginal stop at one letter space distance from the center stop 42. As soon as pressure on the finger lever 5 is released, the detent 25 will move downward into engagement with the stop bar 26 for holding the stop in adjusted position, and the spring 29 will return the bail 28 and detent member 33 to the figure 2 position, disengaging the same from the stops 47. Thus a marginal stop will be locked to the stop bar in position to stop the carriage in the selected letter space position.

In other words, let it be assumed that the 120 machine frame is provided with the usual scale and the carriage with a cooperating pointer, and that it is desired to set the left hand margin stop at the point "20" in said scale. The stops are in locked engagement with the rack bar and the movable detents on the stops are disposed above the detent mechanism so that neither detent will engage said mechanism when the carriage is moved. The operator depresses the margin stop release 125 130

lever 5 which will release the latches of both margin stops from the rack and simultaneously cooperate with the carriage release lever M to release the carriage from its escapement mechanism. Simultaneously with the release of the latches, the detents will be moved downwardly into a position whereby either one of them will engage the detent mechanism upon movement of the carriage.

10 The operator without releasing the lever 5 and the key M, moves the carriage to the right until the detent of the left hand stop engages the detent mechanism. The engagement between the detent of the left hand stop and said detent mechanism prevents further movement of the stop with the carriage, but permits the carriage to be further moved by the operator in the same direction until the pointer on the carriage registers with the number "20" on the scale. The lever 5 is then released by the operator and consequently all of the parts will be returned to their initial positions with the left hand stop locked to the rack. Thereafter, during the regular operation 25 of the machine, the carriage will be moved through its escapement mechanism towards the right until the left hand stop abuts the center stop whereupon the carriage will be stopped at the point "20" on the scale. It will be obvious that should it be desired to 30 adjust the right hand stop for cooperation with a predetermined point on the scale, the same sequence of operations will be employed, although the carriage will be moved in the opposite direction.

It is obvious that the invention may be applied to different types of machines and that various details thereof may be modified so far as the actual structure is concerned without 40 in any way departing from the spirit of the invention, which is to be regarded as limited only by the scope of the appended claims.

I claim as my invention:

1. In a typewriting machine having a margin stop bar, a margin stop adjustable thereon, and carriage release mechanism; the combination of means for releasing the margin stop from the bar which comprises a release bar mounted on and movable longitudinally of the stop bar, manual means for operating the release bar, and means whereby said manual means also operates the carriage release mechanism.

2. In a typewriting machine having a margin stop bar, a margin stop adjustable thereon, and a latch carried by the stop for holding it in adjusted position; the combination of means for releasing the margin stop from the bar which comprises a release bar mounted on and movable both transversely and longitudinally of the stop bar to release said latch, and manual means for operating said release bar.

3. In a typewriting machine having a margin stop bar, a margin stop adjustable there-

on, and a latch carried by the stop for holding it in adjusted position; the combination of means for releasing the margin stop from the bar which comprises a release bar mounted on and movable both transversely and longitudinally of the stop bar to release said latch, a detent carried by said stop and moved to operative position when the stop is released, and detent mechanism on the frame of the machine for engaging said detent.

4. In a typewriting machine, a margin stop bar having a slot extending lengthwise thereof, a margin stop on said bar, a latch for holding said stop in adjusted position, a release bar mounted in said slot, and means for moving said release bar endwise to move said latch to releasing position and permit adjustment of said stop.

5. In a typewriting machine, a margin stop bar having a slot extending lengthwise thereof, a margin stop on said bar, a latch for holding said stop in adjusted position, a release bar mounted in said slot, means for moving said release bar endwise, and means whereby the endwise movement of said bar also moves it in another direction to release said latch.

6. In a typewriting machine, a margin stop bar having a slot extending lengthwise thereof, a margin stop on said bar, a latch for holding said stop in adjusted position, a release bar mounted in said slot, a detent carried by said stop, detent mechanism on the frame of the machine, and means for moving said release bar to release said latch and simultaneously move the detent into position to engage the detent mechanism.

7. In a typewriting machine, a main frame, an endwise movable margin stop bar, a margin stop thereon, means for normally holding the stop in fixed relation to the bar, a detent on said stop, detent mechanism on the frame of the machine including spring pressed dogs, and means for releasing said stop from the bar and for simultaneously moving the detent into position for engagement between said dogs upon the movement of the bar in either direction.

8. In a typewriting machine, the combination with a main frame, of a carriage movable on said main frame, an escapement mechanism for the carriage, means for releasing the carriage from the escapement mechanism including a carriage release key, a margin stop bar movable with the carriage, a margin stop adjustably mounted on the bar for movements longitudinally thereof, a latch carried by the stop for locking the same in any position of adjustment along the bar whereby said stop will be normally moved with the carriage, means for releasing the latch from the bar including an actuating lever cooperating with the carriage release key to simultaneously operate the carriage release mechanism, and a detent mechanism engageable by said stop during movement of the carriage in one

direction to retain said stop against further movement with the carriage during said carriage movement.

9. In a typewriting machine, the combination with a main frame, of a carriage movable on said main frame, an escapement mechanism for the carriage, means for releasing the carriage from the escapement mechanism including a carriage release key, a margin stop bar movable with the carriage, a margin stop adjustably mounted on the bar for movements longitudinally thereof, a latch carried by the stop for locking the same in any position of adjustment along the bar whereby said stop will be normally moved with the carriage, a detent mechanism, a detent movably mounted on the stop and normally disposed out of the path of engagement with said detent mechanism, and means for releasing the latch from the bar including an actuating lever cooperating with the carriage release key to simultaneously operate the carriage release mechanism and for moving the detent into the path of the detent mechanism whereby the stop will be retained against further movement with the carriage during the carriage movement in one direction.

10. In a typewriting machine, the combination with a main frame, of a carriage movable on said frame, an escapement mechanism for the carriage, means for releasing the carriage from the escapement mechanism including a carriage release key, a margin stop bar movable with the carriage, margin stops independently adjustable on the bar, a latch carried by each stop for locking the stop in any position of adjustment along the bar, means for simultaneously releasing the latches of both stops from the bar including an actuating lever cooperating with the carriage release key to simultaneously operate the carriage release mechanism, and a detent mechanism located intermediate said stops and engageable by one stop only during movement of the carriage in one direction to retain the said stop against further movement with the carriage during said carriage movement.

11. In a typewriting machine, the combination of a carriage and an escapement mechanism therefor, and manually operable means for releasing the carriage from the escapement mechanism, said carriage including a margin stop bar and a margin stop adjustable thereon; and manually operable means for releasing the margin stop from the stop bar and arranged in cooperative relation with the carriage release means whereby both release means will be operated simultaneously upon operation of the stop release means, the carriage release means being operable independently of the margin stop release means.

12. In a typewriting machine, the combination of a carriage and an escapement

mechanism therefor, and means including a manually operable lever for releasing the carriage from the escapement mechanism, said carriage including a margin stop bar and a margin stop adjustable thereon; and means including a manually operable lever for releasing the margin stop from the stop bar and arranged in cooperative relation with the carriage release lever whereby both release means will be operated simultaneously upon operation of the stop release lever, the carriage release lever being operable independently of the margin stop release lever.

13. In a typewriting machine, the combination of a frame, a carriage and an escapement mechanism therefor, a center stop, and manually operable means for releasing the carriage from the escapement mechanism, said carriage including a margin stop bar and a margin stop adjustable thereon; manually operable means for releasing the margin stop from the stop bar and arranged in cooperative relation with the carriage release means whereby both release means will be operated simultaneously upon operation of the stop release means, the carriage release means being operable independently of the margin stop release means, detent mechanism other than the center stop and mounted on the frame of the machine, and means carried by the margin stop for engaging said detent mechanism when said margin stop is released from the bar.

14. In a typewriting machine, the combination of a frame, a carriage and an escapement mechanism therefor, a center stop, and means including a manually operable lever for releasing the carriage from the escapement mechanism, said carriage including a margin stop bar and a margin stop adjustable thereon; means including a manually operable lever for releasing the margin stop from the stop bar and arranged in cooperative relation with the carriage release lever whereby both release means will be operated simultaneously upon operation of the stop release lever, the carriage release lever being operable independently of the margin stop release lever, detent mechanism other than the center stop and movable on the frame of the machine, a detent on said margin stop normally out of the path of the detent mechanism, and means whereby the margin stop release means moves said detent into operative position for engagement with the detent mechanism to stop further movement of said margin stop.

In testimony whereof, I have hereunto subscribed my name.

GILBERT M. SCHERER.
